UNITED STATES PATENT OFFICE.

ERNST G. K. ANDERSON, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

"SE-PLUG.

1,335,810.

Specification of Letters Patent.

Patented Apr. 6, 1920.

Application filed May 8, 1915, Serial No. 26,762. Renewed April 24, 1918. Serial No. 230,610.

To all whom it may concern:

Be it known that I, ERNST G. K. ANDERSON, a citizen of the United States, residing at Chicago, in the county of Cook and State of Illinois, have invented new and useful Improvements in Fuse-Plugs, of which the following is a full, clear, concise, and exact description, reference being had to the accompanying drawing, forming a part of this specification.

10 My invention relates to fuse plugs.

Among the objects of my invention is to provide a fuse plug which shall be simple in construction and efficient in use.

15 Further objects will appear from the detailed description to follow and from the appended claims.

In the drawings, in which I have illustrated an embodiment of my invention—

20 Figure 1 is a side elevation of a fuse plug, part of the insulating band being broken away to show the split shell portion;

25 Fig. 2 is an axial section of the plug showing the manner in which the fuse carrier is detachably held in the shell;

Fig. 3 is a section on the line 3—3 of Fig. 2, showing the arrangement of the fuses and center contact; and

30 Fig. 4 is a section on the line 4—4 of Fig. 2, showing the inter-engaging positioning means on the carrier and shell.

Referring now to the drawings in detail, the plug comprises a threaded contact shell 10 for engagement with the threaded contact 35 of a receptacle, an insulating cap or button 11 secured to the shell 10, a center contact 12 supported by the cap 11, a fuse carrier 13 rotatably mounted in the contact 10, a plurality of fuses 14 supported by the carrier 13, and a thumb piece 15 secured to the carrier for rotating the latter to bring the different fuses into electrical connection with the center contact 12. The center contact 12 is electrically connected to the fuses 40 through a conductor 16 which is held on the cap 11 and electrically connected with the contact 12 by means of a hollow rivet or eyelet 17. The lower end of the conductor 16 is bent outwardly as shown at 45 to form a contact for engagement with the upper ends of the fuses 14 which are seated in openings 19 extending through the carrier 13. The upper ends of the fuses 14 extend into and are secured to eyelets 20 50 in any suitable manner, which eyelets extend

downwardly into the openings 19 and are flanged over at their upper edges, as shown at 21, for engagement with a plate 22 of mica or other suitable material, to hold the plate in place on the carrier 13. The lower portion of the shell 10 is split in several 60 places as shown at 23 (Figs. 1 and 4) whereby spring tongues 24 are provided to hold the carrier 13 in position within the shell 10. The thumb piece 15 comprises an 65 insulating washer 25 having an opening 26 therein through which extends a neck portion 27 formed integral with the conducting member 28 which electrically connects the fuses 14 with the shell contact 10, the neck 70 portion 27 being flanged over, as shown at 29, beneath the insulating washer 25 to hold the latter in position. The conducting member 28 has an annular portion 30 extending upwardly therefrom for snap engagement with the spring tongues 24, as clearly shown in Fig. 2, whereby the carrier is rotatably and detachably held in position within the shell 10. The lower portion of the carrier is slightly enlarged as 75 shown at 31, and the upper edge of the annular portion 30 is flanged thereover, as shown at 31^a, to securely hold the conducting member 28 on the carrier. A plate 32 of mica or other suitable insulating material is placed beneath the washer 25 and is held thereon by means of a retaining member 33 having an annular portion 34 surrounding the washer 25 which portion is 80 flanged over as shown at 35 to securely hold 85 the retaining member and mica plate in position on the washer 25.

The annular portion 34 may be milled, if desired, as shown at 36 to form a suitable gripping surface. One of the tongues 24 95 is struck inwardly to form a projection 37 for engagement with the depressions 38 (Fig. 4) in the annular portion 30, the relation of the depressions 38 and the fuses 14 being such that when the projection 37 100 engages one of the depressions 38 one of the fuses 14 will be in electrical connection with the center contact 12.

The use and operation of my improved plug is as follows: When the plug is 105 screwed into the receptacle the circuit through the plug is from the center contact 12, through the eyelet 17, conductor 16, fuse 14, and conducting member 28, to the shell contact 10. In case one of the fuses 110

- is blown the carrier 13 is rotated by means of the thumb piece 15 to bring a new fuse into electrical connection with the center contact 12, the projection 37 on the shell 10 engaging one of the depressions 38 in the annular portion 30 to properly position the carrier. After all of the fuses have been blown the carrier may be removed from the shell 10 by simply pulling outwardly on the thumb piece 15, the spring tongues 24 yielding to permit the carrier to be withdrawn. The shell 10 may be left in the receptacle and a new carrier inserted in the old shell.
- 15 It will be noted that the lower ends of the fuses 14 will be visible through the transparent mica insulation 32 so that it can be determined, by inspection, when the fuses have been blown.
- 20 Having thus described my invention what I claim as new and desire to secure by Letters Patent is:—
1. A multiple fuse plug comprising a shell contact, and a center contact at one end of said shell contact, a plurality of fuses, and a fuse carrier for said fuses insertible within said shell contact at the end opposite said center contact and movable to different positions to bring the different fuses successively into circuit.
  2. A multiple fuse plug comprising a shell contact, and a center contact at one end of said shell contact, a plurality of fuses, a fuse carrier for said fuses insertible within said shell contact at the end opposite said center contact and movable to different positions to bring the different fuses successively into circuit, and means for detachably holding said fuse carrier in said shell contact.
  3. A multiple fuse plug comprising a shell contact, and a center contact at one end of said shell contact, a plurality of fuses, a fuse carrier for said fuses insertible within said shell contact at the end opposite said center contact, and means for detachably and rotatably holding said fuse carrier in said shell contact.
  4. A multiple fuse plug comprising a shell contact, and a center contact at one end of said shell contact, a plurality of fuses, a fuse carrier for said fuses insertible within said shell contact at the end opposite said center contact and movable to different positions to bring the different fuses successively into circuit, and yielding means for detachably holding said fuse carrier in said shell contact.
  5. A multiple fuse plug comprising a shell contact, a center contact, a fuse carrier rotatably mounted in said shell contact, a plurality of fuses supported by said carrier, and means including a contact located eccentrically with respect to the axis of said fuse-carrier and electrically connected to said

center contact whereby as said carrier is rotated the different fuses will be brought successively into electrical connection with said center contact.

6. A multiple fuse plug comprising a center contact and a shell, one portion of which forms a contact for engagement with the shell contact of the socket, and another portion of which is split to form spring tongues, a plurality of fuses, and a fuse carrier for said fuses insertible within said shell and held therein by said spring tongues.

7. A multiple fuse plug comprising a center contact, and a shell, one portion of which forms a contact for engagement with the shell contact of a socket, another portion of which is split to form spring tongues, a plurality of fuses, and a fuse carrier for said fuses insertible within said shell, said fuse carrier having an annular portion engaging said spring tongues to hold the carrier rotatably in said shell.

8. A multiple fuse plug comprising a center contact, and a shell, one portion of which forms a contact for engagement with the shell contact of a socket, another portion of which is split to form spring tongues, and a fuse carrier insertible within said shell, said fuse carrier having an annular portion engaging said spring tongues to hold the carrier rotatably in said shell, said annular portion having circumferentially spaced positioning means, and said split portion having positioning means co-operating with said first positioning means, and means whereby as said carrier is rotated the different fuses will be brought successively into the circuit.

9. A multiple fuse plug comprising a center contact, and a shell, one portion of which forms a contact for engagement with the shell contact of a socket, another portion of which is split to form spring tongues, and a fuse carrier insertible within said shell, said fuse carrier having an annular portion engaging said spring tongues to hold the carrier rotatably in said shell, said annular portion having a plurality of circumferentially spaced depressions and said split portion having a projection engaging said depressions to position the carrier, and means whereby as said carrier is rotated the different fuses will be brought successively into the circuit.

10. A multiple fuse plug comprising a threaded shell contact, a cap therefor at one end thereof, a center contact supported by said cap, a plurality of fuses, a fuse carrier for said fuses insertible within said shell contact at the end opposite said center contact, yielding means for detachably and rotatably holding said fuse carrier in said shell contact, and contact-making means whereby as said carrier is rotated the different fuses will be brought successively into the circuit.

11. A multiple fuse plug comprising a shell contact having an annular contact portion, a fuse carrier rotatably mounted in said shell contact, a plurality of fuses supported by said carrier, means whereby all of said fuses are in electrical connection with said annular contact portion, and contact-making means whereby as said carrier is rotated the different fuses will be brought successively into the circuit.

12. A multiple fuse plug comprising a shell contact having an annular contact portion, a fuse carrier rotatably mounted in said shell contact, a plurality of fuses supported by said carrier, means whereby all of said fuses are in electrical connection with said annular contact portion, said means including a contact slidably engaging said annular contact, and contact-making means whereby as said carrier is rotated the different fuses will be brought successively into the circuit.

13. A multiple fuse plug comprising a shell contact having an annular contact portion, a fuse carrier rotatably mounted in said shell contact, a plurality of fuses supported by said carrier, means whereby all of said fuses are in electrical connection with said annular contact portion, said means including an annular sheet metal contact surrounding the end of said carrier and rotatably engaging said first annular contact, and contact-making means whereby as said carrier is rotated the different fuses will be brought successively into the circuit.

14. A multiple fuse plug comprising a shell contact having an annular contact portion, a fuse carrier rotatably mounted in said shell contact, a plurality of fuses supported by said carrier, and means whereby all of said fuses are in electrical connection with said annular contact portion, said means including an annular sheet metal contact surrounding the end of said carrier and rotatably engaging said first annular contact, a thumb piece for rotating said carrier having an opening therein, said second annular sheet metal contact having means integral therewith and extending into said opening for securing the thumb piece to the carrier.

15. A multiple fuse plug comprising a shell contact and a center contact at one end of said shell contact, a plurality of fuses, a fuse carrier for said fuses insertible within said shell contact at the end opposite said center contact, means for detachably and rotatably holding said fuse

carrier in said shell contact, and a thumb piece secured to said carrier for rotating it, and contact-making means whereby as said carrier is rotated the different fuses will be brought successively into the circuit.

16. A multiple fuse plug comprising shell and center contacts, a plurality of fuses, and a fuse carrier for said fuses movable to different positions to bring the different fuses into circuit, said fuse carrier having a snap connection with respect to said shell contact.

17. A multiple fuse plug comprising shell and center contacts, a plurality of fuses, and a fuse carrier for said fuses insertible within said shell and movable to different positions to bring the different fuses successively into circuit, said fuse carrier having a snap connection with respect to said shell contact.

18. A multiple fuse plug comprising a shell contact and a center contact at one end of said shell contact, a plurality of fuses, and a fuse carrier insertible within said shell contact at the end opposite said center contact and movable to different positions to bring the different fuses successively into circuit, said fuse carrier having a snap connection with respect to said shell contact.

19. A fuse plug comprising a plug-in portion having an insulating base and a contact supported thereby for engagement with a receptacle contact, a fuse support comprising an insulating base, a plurality of fuses supported thereby, and a quick-detachable connection between said plug-in portion and said fuse support.

20. A fuse plug comprising a plug-in portion for engagement with the contact of a receptacle, a fuse support, a plurality of fuses supported thereby, and a quick-detachable snap connection between said fuse support and plug-in portion.

21. A multiple fuse plug comprising a plug-in portion having a contact for engagement with the contact of a receptacle, a plurality of fuses, and a fuse-carrier for said fuses having a quick-detachable connection with said plug-in portion, said fuse-carrier being capable of quick detachment with respect to said plug-in portion when said plug-in portion is positioned in the receptacle.

In witness whereof I have hereunto subscribed my name.

ERNST G. K. ANDERSON.
